UNITED STATES PATENT OFFICE.

WALTER B. STRAUB, OF POTTSVILLE, PENNSYLVANIA, ASSIGNOR OF ONE-HALF TO
FRANK C. YINGST, OF PORT CARBON, PENNSYLVANIA.

UNION-GARMENT.

1,278,249.

Specification of Letters Patent. Patented Sept. 10, 1918.

Application filed August 11, 1913. Serial No. 784,222.

To all whom it may concern:

Be it known that I, WALTER B. STRAUB, a citizen of the United States, and a resident of Pottsville, in the county of Schuylkill and State of Pennsylvania, have made certain new and useful Improvements in Union-Garments, of which the following is a specification.

My invention relates to union garments—that is, to garments made in practically one piece and serving the purpose of a plurality of separate under garments.

More particularly stated, I seek to produce a union garment in which the strains due to bending the body of the wearer are so distributed as to avoid unduly distorting the garment or allowing the garment, owing to strains upon it, to distort other parts of the cloth or to cause discomfort of the wearer.

I further seek to so distribute the strains as to increase the durability of the garment and to cause the garment to maintain a comparatively neat appearance.

I also seek to give the garment such shape that in manipulating it the wearer is discommodeed to the slightest possible extent. These and other objects of the invention are more clearly brought out in the following description.

Reference is made to the accompanying drawing forming a part of this specification, and in which like letters indicate like parts.

Figure 1 is a fragmentary perspective showing the garment in use as it appears when the wearer is bending his body sideways to an unusual extent.

Fig. 2 is a rear elevation of the main portion of the garment as it appears when the wearer stands erect, and Fig. 3 is a perspective view of the garment from the rear, a part of the upper portion of the garment being broken away.

The front 9 of the garment and the upper back portion 10 are secured together by vertical side seams. A band 11 of knit, woven, or other very elastic fabric is connected with the lower edge of the back portion 10. A broad band 12 is attached to the elastic 11, the ends of the same being secured to the side edges of the front 9, as will be readily understood.

The leg trunk 13 is formed by the downward continuation of the front 9 and by the back portion extending forward in the form of a broad flap. The triangular piece

or gore 14 is attached along one edge to the front 9 and at its upper edge to the elastic band 11, so that its inner side has an oblique position. The adjacent portion of the flap is an obtuse angle, its side edge and the gore meeting on the oblique line. The flap is secured to the upper inner corner of the gore 14 by means of a single button 16, which passes through a button-hole 17 in the flap.

A tape strip 14^a extends along another edge of the gore piece and well down into the adjacent leg trunk 13 to which it is firmly secured. The garment is provided with an opening 14^b below the back member 12 and is provided with a flap 15 for the purpose of closing said opening. This opening, upon its side to the left, is secured directly to the back member 12 and reaches to the upper edge of the same.

The flap may be raised or lowered, as will be understood from Figs. 1 and 3. A button 16 is mounted upon the gore piece 14 at a point adjacent one of the upper corners thereof and the flap 15 is provided with a button hole 17 for mating this button.

As may be understood from Fig. 2 the flap 15, though reaching at the left side into engagement with the left edge of the front facing 9, does not reach entirely across to the right. That is to say, the flap 15 merely reaches a little beyond the adjacent edge of the gore piece 14, the flap and the gore piece together reaching entirely across the garment from side to side.

When a person wearing this garment bends over, as indicated for instance in Fig. 1, there is of course some strain thrown upon the garment. Owing however, to the location and structure of the gore piece 14 and parts immediately associated therewith, the strain is transmitted downwardly through this gore piece to the adjacent leg trunk 13, as may be understood from Fig. 1. Owing to the permanent connection between the opposite edge of the flap and the adjacent parts (see left of Fig. 2) the strain will be well distributed on the left side according to this figure, if the wearer of the garment should bend to the right.

In practice all that is necessary in order to lower the flap 15 is to release a single button and in restoring the flap to normal position this button is pushed through the button hole 17.

As shown in Figs. 1 and 2, the button 16

2
is located a considerable distance from the vertical side seam of the garment and attached, as before stated, to the corner of the gore. In other words, the button 16 is located at a point about half way between the middle of the back and a side seam of the garment. This location avoids the necessity for using more than one button to hold the flap properly closed, and at the same time the strain on the flap, which is incident to use of the garment when the wearer is seated, is applied to the elastic band 11, and in fact to the whole upper back portion of the garment.

15 I claim:

1. In a union garment comprising a body having the usual front, legs, and upper back portion, a transverse elastic band secured to and pendent from the back portion, a substantially triangular gore whose side edge is secured to the front and at its top to the lower edge of the elastic band, a single flap whose free portion forms an obtuse angle, and a button for securing said flap at its corner, the same being located at the inner upper corner of the gore and thus at a point between the middle and side of the garment.

2. A union garment comprising a body having the usual front, legs, and upper back portion, a substantially triangular gore secured along one side edge to the front of the garment and at its top edge to the back portion of the same, and a single flap whose free edge forms an obtuse angle, one edge of which, when the flap is closed, overlies the oblique edge of the gore, and a button located at the upper acute angle of the gore and serving to secure the flap in closed position, as described.

3. A union undergarment having a permanently closed crotch, an opening whose upper edge extends only partially across the back of the undergarment and termi-

nates at one end short of the side line of 45 said garment, the opening at such side of the garment then extending down to the outside of one of the legs, the latter being permanently closed below the terminus of said opening, and means for detachably 60 fastening the drop seat flap defined by said opening.

4. In a garment having a posterior opening, a flap for closing said opening, the said flap integral with the crotch portion of the 55 garment and permanently fastened along the whole of one of its lateral edges and along the other lateral edge up to a point above the crotch, the said flap presenting a side opening extending from the said 60 point to the upper end of the last named lateral edge and detachably secured to the garment at its said upper end of said edge, the said flap providing a sufficient fullness to afford the required posterior opening 65 when the flap is folded back along a line reaching from the said point on one lateral edge of the flap to the upper end of the said permanently fastened lateral edge.

5. A union undergarment having a permanently closed crotch and a back opening whose upper edge extends from one side of the garment only partially across the back and terminates at its other end at a distance from the other side of the garment with 75 the side of the opening extending from such end of the top edge to the outside of the adjacent leg of the garment and the lower end of said leg being permanently closed; a flap for closing said back opening 80 and means for detachably fastening said flap.

WALTER B. STRAUB.
